AUTOMATIC STRIP STARTER

George W. Moore, Wintersville, Ohio, assignor of
ten per cent to Sallie B. Moore and ten per cent
to Howard Nelson Moore, both of Ruxton, Md.

Application July 9, 1951, Serial No. 235,884

33 Claims. (Cl. 242—78)

1

The present invention concerns a strip starter useful in continuous strip mills in the metal industry and although it has particular application to the large cold strip mills of the steel industry it will be readily understood by those skilled in the art to be equally applicable to hot strip mills and to mills in which non-ferrous metals are worked. Again, the invention is a strip starter and is therefore equally applicable to those mills employing a series of roll stands through which the strip passes once and those mills having only one or a few roll stands through which the strip is passed back and forth until the desired gauge and finish is obtained.

The stock to be worked upon is delivered to the work space or area in a coil which is often bound with wire or bands to prevent unrolling. With the smaller sizes of coils, those of light gauge and narrow width, many times all that is necessary is to place the coil bundle on a proper size reel, cut the binding wires and enter the end of the strip into the feed of a press, the first roll stand or other machine as the case may be, by hand.

If, however, as is often the case, one must deal with strip stock where the coil of stock may weigh several tons, be four or five feet wide and the strip itself have a thickness of $\frac{1}{8}$ inch or more, the handling of the coil and starting the end into the feed of a machine can present quite a problem. At present this problem is solved by having enough husky men on the job to manhandle the coil to proper position, pull the end away from the body of the coil, straighten the first few feet in an operation called "breaking its back" and starting the straightened end into the feed of the machine or the bite of the rolls. The starting of the strip is an operation that is required in many operations where metal is worked or processed such as picking, rolling, polishing, slitting etc. As stated this operation of starting is now done by hand and requires fifteen to twenty percent of the total mill time required to process a coil.

It is an object of the invention to provide a strip starter which will eliminate the handling above described, position the coil, pry out the end, "break its back" and feed the free end to the feed of a press, bite of a working or feed roll, etc.

It is an object of the invention to provide a strip starter which is fully automatic in its operation or one in which many of the steps are under the direct operational control of an operator as may be desired.

2

Reference is made to the drawings which are to be taken as illustrative and not as limiting. Like numerals refer to like parts throughout.

In the drawings:

5 Fig. 1 is an elevation of one form of fully automatic machine.

Fig. 2 is a circuit diagram of an automatic control for the machine of Fig. 1.

10 Fig. 3 is a fragmentary elevation of a variant form of a detail of Fig. 1.

Fig. 4 is an elevation of another form of strip starter.

Fig. 5 is a control panel circuit diagram.

15 Fig. 6 is a fragmentary plan view of rack and gearing detail of Fig. 3.

Fig. 7 is a fragmentary plan view of a portion of Fig. 4.

20 One form of the invention shown in Fig. 1 comprises an inclined runway 10 on which coils 11 of steel strip are rolled or placed by a crane in side by side relation with an end 12 of the strip extending from each coil 11 in a clockwise direction. Ends 12 are usually tight to the coil, but where they extend more than six or eight 25 inches from the body of their coil 11 they may be hammered back. Coils 11 are preferably unbanded after spotting on runway 10 thus reducing the likelihood of undue freedom of end 12 in the lighter gauges. Coils 11 have a central 30 channel 13.

Coils 11 are held from rolling down runway 10 by a plunger 14 which is biased by a tension spring and operated by a solenoid or air cylinder 15. A second similarly biased plunger 16 and 35 solenoid 17 assure that the coils 11 are fed one at a time. When a coil 11 is released by the second plunger 16 the coil rolls down runway 10 until it comes to rest in shallow depression 18. Curved arms 19 prevent over running and 40 will return a coil to depression 18 which is centered just above lift table or platform 20 mounted on a long worm 21 actuated by an internally threaded worm wheel 22 driven by worm 23 on the shaft of motor 24 mounted on frame member 45 25.

Lift table 20 is curved on its upper surface to receive coils 11 of varying diameters. Frame 25 carries a selsyn pair 26, 27 which may be related mechanically through a suitable linkage, a flexible cable, or connected electrically as shown. Selsyn 26 has a feeler arm 28 which projects toward the center of a coil 11 resting on curved depression 18 and performs the double function of determining whether or not a coil is present in 55 depression 18 and also the radius or diameter of

any coil 11 which may be positioned in depression 18.

Lift table 20 raises a coil 11 from depression 18 to proper position between trunnions 68 mounting tapered projecting arbor portions 29 of stub shafts 30 which are designed to enter the two ends of channel 13 of the coils 11, and support the coils for rotation. Lift table 20 raises coil 11 until arm 31 trips switch 32 which is positioned vertically by selsyn 27. Trip switch 32 is a multiple switch which breaks the circuit of motor 24 when channel 13 is aligned with arbors 29 and energizes motor 33 which acts through worm 34 and worm wheel 35 to move the trunnions 68 towards each other and to cause the arbors 29 to enter the channels 13 and support a coil 11. When trunnions 68 have moved inward far enough so that arbors 29 have gripped the inner wall of channel 13 the projecting arm 36 of multiple switch 37 breaks the circuit of motor 33 and closes a reversing circuit of motor 24 thus stopping motor 33 and returning lift table 20 to its normal position. Switch 33 serves the double function of opening the reversing circuit of motor 24 when lift table 20 is in its lower position and opening the circuits of solenoids 17 and 15 when lift table 20 is raised from its coil receiving position.

Multiple switch 37 also closes the circuit of motor 39 which drives the stub shafts 30, face plates 40, arbors 29 and the coil 11 supported therebetween in a clockwise direction as shown in Fig. 1. Switch 37 also closes a circuit which energizes solenoid or air cylinder 41 and moves the scraper or peeling assembly toward rotating coil 11, compressing return spring 42. The element 41a in Fig. 2 represents the solenoid of element 41 of Fig. 1 or where 41 is an air cylinder as shown 41a represents a solenoid operated air valve therefor. This action slides plate 43 over frame 25 and presses nose portion 44 against the moving side of coil 11. When end 12 reaches nose portion 44 it is peeled off and slides along plate 43.

In the event end 12 is below the nose 44 before it is pressed against the coil 11, curved guide 45 serves to press the end 12 towards the body of the coil 11 so that it will stay in place for a complete revolution until the end 12 reaches the nose 44 from a clockwise direction. While it is preferred to have the coil 11 rotate initially in a clockwise direction it may be desirable with light gauges first to rotate it counterclockwise until the end 12 trips a feeler switch such as 46 to reverse motor 39 to turn strip coil 11 clockwise and to advance plate 43 with its nose 44. This would prevent a cobble when end 12 is initially just below nose 44 and has bound itself between guide 45 and the body of coil 11. Although feeler switch 46 is thought unnecessary for this purpose in the usual installation it would be a good thing to give the machine attendant overriding control both to stop the entire operation or reverse motor 39 to prevent an impending cobble. Feeler switch 46 serves another purpose in Figs. 1 and 2.

As end 12 passes nose 44 and advances along plate 43 between flange guide 47 it trips switch 48 which actuates solenoid or air cylinder 49, energizes motor 50 and opens the circuit of motor 39. Motor 50 is mounted on sliding plate 43 and geared to roll 51 which it rotates in a clockwise direction as viewed in Fig. 1. Air cylinder 49 acts on the short arm 52 of bell crank 53 which is pivoted at 54 on plate 43, being movable therewith. Bell crank 53 is rotated counterclockwise and 75

carries roll 55, rotatably mounted in slot 56, down against the steel strip which is gripped between the two rolls 51 and 55. Roll 51 has a spur gear 57 mounted on the same shaft which mates with spur gear 58 similarly mounted with respect to roll 55. As the rolls 51 and 55 are pressed together by bell crank 53 spur gears 57 and 58 mesh and motor 50 drives both rolls 51 and 55 at a speed to feed the steel strip at the required number of lineal feet per minute to correspond to the surface speed of rolls 59 and 60 of the first roll stand 61. Roll 55 and gear 58 are mounted in a bearing slidable in slot 56 against a spring. This movement will eliminate what possibility there is that the teeth of gears 57 and 58 might not mesh easily. The steel strip is now fed along plate 43 by rolls 51 and 55. Arm 62 is moved a distance to correspond to the width of the strip and is connected to adjust guides 63 forming part of first roll stand 61. The strip passes along plate 64, between first stand guides 62 and enters the first roll stand 61 where it is gripped by working rolls 59 and 60.

As the end of the strip leaves roll stand 61 it trips switch 65 which opens the circuits closed by switch 48, releasing air cylinder 49 and permitting bell crank 53 to rotate clockwise under the action of spring 66. The circuit of motor 50 is opened and both rolls 51 and 55 are deenergized. Switch 65 does not close the circuit of motor 39 which is still opened by switch 48 as long as its arm is depressed by the presence of steel strip above it. Of course the attendant can exercise independent control of motor 39 and adjust the tension on the strip of coil 11 between the coil and roll stand 61 by applying a braking action through the reversal of motor 39 with a small current.

When the end of the steel strip forming a coil 11 passes by switch 66 its feeler arm rises and a new cycle is initiated. When the attendant turns his control switch 67 to "automatic" switch 66 functions to return all parts of the machine to normal and closes the starting circuit of motor 24. However, arm 28 of selsyn 26 operates a switch which opens the circuit of motor 24 when spring pressed arm 28 is extended its full length in the absence of a coil 11 in depression 18. When arm 28 is fully extended it closes the circuits of solenoids 15 and 17 unless they are open at switch 38 by the elevation of lift table 20. Coils 11 advance as stops 14 and 16 are drawn down and are checked again as soon as a coil 11 moves arm 28. The springs on solenoids 15 and 17 are preferably tension springs which hold the plungers in raised position.

Fig. 2 shows one form of circuit diagram which may be used to provide full automatic control for the apparatus of Fig. 1. Supply line 100 has a line switch 101 on the attendant's panel 102. Although the circuit of Fig. 2 is shown as D. C. or single phase A. C., with the exception of selsyn motors 26, 27, 62a and 63a, it will be understood that the circuit is representative and the apparatus may be wired for three phase A. C. or all three types of power supply may be used in conjunction as may be convenient or desirable.

Coil lift motor 24, is provided with leads 103 and 104 and is connected across line 100 by wire 105 leading to junction 106 and wire 107 leading to junction 108. Wire 107 has switches 28b and 32a in series and then branches at junction 109 into parallel wire 110 having switch 68 in circuit and parallel wire 111 having switch 67 in circuit, both wires 110 and 111 being connected to the

other wire of line 100 than to wire 165. This circuit comprises the direct or lift circuit of motor 24 and is normally closed by automatic switch 66 when the switch arm rises under spring action after the end of a coil has passed over it. However, for the motor 24 to operate to lift a coil 11 into position contacts 28b must be closed showing that there is a coil 11 in position in depression 18 of runway 10 and contacts 48d must be closed showing that the previous coil has been completely unreeled from arbors 29. Contacts 32a are normally closed at the start and serve to stop the lift of a coil 11 by opening the direct drive or lift circuit of motor 24 at the proper time. If all is in order the operator can anticipate the action of automatic switch 66 by closing switch 67 if he desires. It is important that the kinematic cycle of the machine as well as the instant of initiation and duration of the individual events and the operation of the various switches, relays, solenoids and cylinders be so arranged and correlated that there is sufficient time clearance to cause the machine to operate smoothly, but not so much clearance that the complete cycle is unduly prolonged.

Switch 38 has two sets of contacts, *a* which is open and *b* which is closed when its spring biased arm is raised. Switch 38 is positioned under lift table 20 adjacent its coil receiving position so that when lift table or platform 20 is in position to receive a coil 11 the spring biased arm of switch 38 is depressed with contact 38a closed and contact 38b opened. Switch arm 28 has two sets of contacts, *a* which are closed and *b* which are open when moved to the right by its spring bias in the absence of a coil 11 in depression 18. When contacts 28a and 38a are both closed, solenoids 15 and 17 are connected in series by wire 114 and are connected to supply line 100 by wires 112 and 113. Solenoids 15 and 17 are then energized and depress plungers 14 and 16 against their springs, permitting a coil 11 to roll into depression 18 where it moves switch arm 28 to the left, opening contacts 28a and closing twin contacts 28b and 28c. This action opens the circuit of solenoids 15 and 17 and closes contacts 28b in the lift circuit of motor 24.

As switch arm 28 moves to the left under the action of a coil 11 in depression 18 it rotates selsyn motor 26 by an amount equal to the radius of coil 11. Arm 28 is maintained in its left radius indicating position by a locking solenoid 115 which is provided with a delay condenser 116 to allow for oscillations which may occur in coil 11 reaching equilibrium position in depression 18. Solenoid 115 is connected to line 100 by wires 117 and 118, the last containing switch contacts 32c and 28c. Contacts 32c are closed at the start of operations. The closing of contacts 28c and by a coil 11 moving into position energizes locking solenoid 115.

Selsyn 26 is connected by line 119 to selsyn 27 which through arm 120 bodily moves switch 32 upward a distance to correspond to the coil radius as indicated by switch arm 28 and maintained by locking solenoid 115.

Switch 32 has a spring biased arm which, when raised by arm 31 carried by lift table 20, pivots to open contacts 32a in the direct drive circuit of lift motor 24, to close contacts 32b in the direct drive circuit of trunnion motor 33 and to open contacts 32c in the circuit of Selsyn locking solenoid 115. The opening of contacts 32c in wire 118 allows the selsyn pair 26-27 to return under the action of the spring biased arm 28 and lift table 20 is slotted

to pass the extended arm 28 on return to coil receiving position.

Trunnion motor 33 has leads 121 and 122 connected to line 100 by wire 123 which meets lead 121 at junction 124 and wire 125 which meets lead 122 at junction 126. Wire 125 has initially open contacts 32b and initially closed contacts 37a in its circuit. Leads 121 and 122 are connected to a reversing circuit comprising wires 127 and 128 from supply line 100. Wire 127 has initially closed contacts 48c in its circuit and feeler switch 46. Feeler switch 46 opens at about the same time as switch 32 is actuated by arms 31. Switch 32 closes contacts 32b and operates motor 33 to advance trunnions 68 and arbors 29 towards coil 11. As the trunnions 68 move from extreme open position automatic stop limit switch 129 in the reversing circuit closes. Stop switch 129 is mounted on frame 25 and is actuated by movement of the trunnions 68 which open the switch when separated far enough to receive the widest coil 11. Switch 129 has contacts *a* and *b* in wires 127 and 128 to prevent short circuit on the closing of contacts 32b in wire 125.

Face plates 40 are mounted on stub shafts 39 adjacent arbors 29 and function to grip the side of the coil 11 lightly. This pressure may be adjusted to increase the gripping of face plates 40 to supplement the action of arbors 29 in channel 13 if desired. Plates 40 are separated from trunnions 68 by springs 130 which are compressed by movement of the trunnions after plates 40 contact the side of the coil 11. Switch 37 is mounted on one trunnion 68 and has an arm 36 which projects towards one plate 40 and is depressed thereby as the separating springs 130 are compressed and actuates switch 37. This action of arm 36 opens contacts 37a in wire 125 of the direct drive circuit of motor 33, closes contacts 37b in wire 131 of the direct drive circuit of motor 39, closes contacts 37c and 37d in the reversing circuit of motor 24, and closes contacts 37e in circuit 132 of the solenoid operated valve 41a of air cylinder 41. As noted above 41 can be a heavy duty operating solenoid if desired in which case 41a becomes a suitable relay.

The reversing circuit of motor 24 comprises wires 133 and 134 connected to supply line 100. Wire 133 contains initially open contacts 38b and has an open end which together with the open end of lead 103 comprise contacts 37d. Wire 134 likewise has a free end which together with the open end of lead 104 comprise contacts 37c.

Motor 39 has leads 135 and 136 which run to a reversing switch 137 on the panel 102. Switch 137 is normally closed to connect motor 39 to drive a coil 11 clockwise. Wire 131, containing initially open contacts 37b and initially closed contacts 48b, connects line 100 at junction 138 with lead 136. One central pole of reversing switch 137 is connected to line 100 by a wire 139 containing a rheostat 140. The other central pole of reversing switch 137 is connected to line 100 by a wire 141 containing a manual switch 142.

Rheostat 140 enables the operator-attendant to adjust the speed of motor 39 and thereby the coil speed where desirable to control the starting of the strip. Reversing switch 137 and rheostat 140 give the operator-attendant an increased measure of control. When strip is running through roll stand 61 rheostat 140 permits adjustment of tension on the strip. Rheostat 140 may be used for emergency control to stop motor 39. Switch 142 gives overriding control to the operator when desired of motor 39 without ref-

ference to switches 37 and 48. Switch 42 is opened for full automatic operation.

Motor 50 has leads 143 and 144 connected to junction 145 with wire 146 and junction 147 with wire 148, respectively. Wires 146 and 148 connect to the solenoid 49a which operates the valve controlling the supply of air to cylinder 49. Wire 146 contains initially open contacts 48a between junction 145 and line 100. Wire 148 contains initially closed switch 65 between junction 147 and line 100.

Selsyns 62a and 63a are connected by a line 149 and adjust the roll stand guide 63 to the width of coil 11 in a well-known manner, the guide 63 being part of a standard mill and well known in the art.

The operation of the strip starter of Figs. 1 and 2 is as follows:

Coils 11 are placed on runway 10 with ends 12 pointing clockwise where, after bands are removed, they run down against stop 14. As lift table 20 is in coil receiving position the arm of switch 38 is depressed. Contacts 38a are closed and contacts 38b are closed. In the absence of any coil 11 in depression 18, arm 28 has moved to the right under spring action, closing contacts 28a and opening twin contacts 28b and 28c. The circuit of solenoids 15 and 17 is thus completed to line 100 through both contacts 38a and 28a and the solenoids operate to draw down plungers 14 and 16 and permit coils 11 to advance. As soon as a coil 11 moves arm 28 to the left it breaks contact 28a and plungers 14 and 16 are returned to stop position under spring action. Plungers 14 and 16 are spaced to obtain the coil distribution shown in Fig. 1. Where coils 11 weighing several tons are processed air cylinders may be used instead of solenoids 15 and 16 and the plunger 14 and 16 provided with a transverse stop bar.

The switch arm 28 is positioned so that the displacement of it to the left by a coil 11 is a measure of the radius or diameter of the coil. This displacement of arm 28 may be from the axis of a coil 11 resting in depression 18 or it may be from a selected point representing the outside of a coil 11 of minimum diameter. Arm 28 moves to the left sharply as a coil 11 rolls into place and rotates selsyn motor 26 an amount determined by the diameter of the particular coil 11 in position on depression 18. Companion selsyn 27 is connected to selsyn 26 by line 119 and moves in the same way to elevate the actuating arm of switch 32 through a suitable worm and rack arrangement indicated at 120. Arm 32 is raised a distance determined by the diameter of the coil 11 which displaces arm 28. Movement of arm 28 to the left closes twin contacts 28b and 28c which are connected in the drive circuit of motor 24 and locking solenoid 115 respectively. As contacts 32c are initially closed the circuit through wires 117 and 118 is complete and locking solenoid is energized and holds arm 28 in its displaced left hand position. Locking solenoid 115 has delay characteristics provided by condenser 116 so that arm 28 is locked only after a coil 11 has come to rest in depression 18 thus eliminating a false indication of coil diameter. However, a tolerance of several inches is permissible in this measurement.

Movement of switch arm 28 to the left closes contacts 28b in the direct drive circuit of lift motor 24. As contacts 48d and 32a are initially closed motor 24 begins to rotate worm 21 and to raise lift table 20 with the coil 11 in depression 18 of runway 10 just above it as soon as the end 75

of the previous coil has left roll stand 61 and allowed switch 66 to close the circuit. The attendant can anticipate the action of switch 66 by closing switch 67 if he wishes.

As lift table 20 rises, the spring biased arm of switch 38 rises, opening contacts 38a in the circuit of solenoids 15 and 17 and closing contacts 38b in wire 133 of the reversing circuit of motor 24. As the coil 11 on table 20 is lifted arm 28 remains in its locked left hand position and table 20 rises until arm 31 trips switch 32.

All the switches are to be regarded as having their actuating arms pivoted at the left except switches 28 and 129 which are direct plunger types. Switches 36, 38 and 48 have their actuating arms depressed and returned by spring bias. Switch 32 has its arm raised by arm 31 and is returned by spring bias.

As coil 11 is raised to position between trunnions 68 it presses against and opens feeler switch 46 in wire 127 of the reversing circuit of motor 33.

The actuation of switch 32 by arm 31 on table 20 opens contacts 32a in the direct drive of motor 24, closes contacts 32b in wire 125 of the direct drive circuit of motor 33 and opens contacts 32c in wire 118 of the circuit of locking solenoid 115.

The opening of contacts 32a stops motor 24 and lift table 20 at a point where the particular coil 11 is in position so that arbors 29 may enter the ends of channel 13. Channel 13 is large enough and arbors 29 have sufficient taper to allow for some inaccuracy in positioning of a coil such as that due to an end 12 being directly against arm 28 when it is measuring coil diameter. A tolerance of several inches is acceptable. Where an end 12 projects too far it is hammered back, but this is infrequent in the heavier gauges and seldom occurs where care is taken in banding and unbanding the coils 11. If desired the attendant can be given a separate control circuit for motor 33 to make any necessary adjustments. Such over-riding control can be provided individually for any of the various motors, solenoids and cylinders.

The closing of contacts 32b energizes motor 33 and causes trunnions 68, bearing stub shafts 30, tapered arbor portions 29, face plates 40 and arm 36 of switch 37 to approach coil 11. The opening of contacts 32c breaks the circuit of locking solenoid 115 which releases slowly because of condenser 116. The delay time of solenoid 115 is sufficient to permit motor 33 time to insert arbors 29 into the ends of channel 13 and press face plate 40 against the coil face and cause it to depress arm 36 of switch 37. As solenoid 115 releases arm 28 is moved to the right by its spring bias, opening twin contacts 28b and 28c and closing contacts 28a. At the same time arm 28 rotates selsyn 26 and lowers the switch arm 32 which is flexible enough to bend and free itself from arm 31 on table 20. The arm of switch 32 operates only when pressed upward and so merely bends again when arm 31 passes it as table 20 is lowered.

Initial movement of trunnions 68 permits the plunger of spring biased stop switch 129 to close contacts 129a and 129b in wires 127 and 128 of the reversing circuit of motor 33. Two contacts 129a and 129b are used to avoid short circuit.

Trunnion motor 33 continues to force arbors 29 into channel 13 and plates 40 against the coil faces until a face plate 40 impinges on arm 36 carried by a trunnion 68. Arm 36 depresses the plunger of switch 37 which opens contacts 37a

in wire 125 of the drive circuit of trunnion motor 22 and closes contacts 37b in wire 131 of the direct drive circuit of motor 39, closes contacts 37c and 37d in the reversing circuit of motor 33 and closing contacts 37e in the control circuit 132 of solenoid valve 41a of air cylinder 41.

When contacts 37a open motor 33 stops and trunnions 68 remain in position as the worm drive is self locking. The closing of contacts 37b places motor 39 across the line as contacts 43b are initially closed and attendant's reversing switch 137 is normally kept closed on the direct drive side until the attendant wishes to take over control. Motor 39 begins to rotate coil 11 in a clockwise direction. The closing of contacts 37c and 37d completes the reversing circuit of lift motor 24 which lowers table 20 until it is below depression 18 of runway 16 and depresses the actuating arm of switch 38, again closing contacts 38a which allows the coils 11 to advance on runway 16 and opening contacts 38b in wire 133 which stops the motor 24. The closing of contacts 37e opens solenoid valve 41a and admits air under pressure to cylinder 41, moving plate 43 towards coil 11 and pressing nose 44 against its side.

As motor 39 rotates coil 11 clockwise the end 12 strikes nose 44 and peels off causing the strip to ride along plate 43. In the event the end 12 slips below the nose 44 curved guide 45 directs the end under the coil and prevents a cobble. The coil continues to rotate and the end 12 strikes the nose 44 again. Only very stubborn cases fail to respond to automatic action. Occasionally the attendant may have to take over and use reverse switch 137 to straighten or smooth an end 12 by dragging it counterclockwise under nose 44. Again where the strip is very heavy and stiff he may open switch 159 on panel 102 and withdraw nose 44 from the coil. Motor 39 may then be speeded up by rheostat 140 and the coil 11 permitted to complete several rotations to build up momentum before switch 159 is closed to again advance nose 44. This treatment will start the most stubborn coils.

As the strip advances along plate 43 between guides 47 the end depresses the actuating arm of switch 48 which closes contacts 48a in the drive circuit of motor 50 and the actuating circuit of solenoid valve 49a, wire 145 being common to both circuits, opens contacts 48b in wire 131 of the drive circuit of motor 33, opens contacts 48c in wire 127 of the reversing circuit of motor 33, opens contacts 48d in the drive circuit of motor 24 and opens contacts 48e in circuit 132 of solenoid valve 41a.

The closing of contacts 48a starts motor 50 which drives roll 51 at a surface speed equal to that of rolls 59 and 60 and actuates cylinder 49 and causes the piston rod to exert a force on arm 52 of bell crank 53 and pivots it counterclockwise about 54 until spur gear 57 meshes with the teeth of gear 58 and roller 55 rests on and turns with roller 51. The slot and spring pressed pillow block 56 in the end of bell crank 53 assure the meshing of gears 57 and 58. Rollers 51 and 55 pinch the strip between them and feed it along plate 43 between flange guides 47. The opening of contacts 48b opens the circuit of motor 39 which ceases to rotate the coil 11. The opening of contacts 48c prevents the premature return of motor 33 and the opening of contacts 48d prevents the premature raising of a second coil 11 by motor 24. The opening of contacts 48e withdraws nose 44 so it will not scratch the

surface of the steel strip. Solenoid valve 41a deenergizes and permits spring 42 to move plate 43, nose 44 and roll assembly 51, 55 to the right until stop lug or arm 151 strikes plate 64.

As the strip passes between arms 62, selsyn 62a and selsyn 63a adjust the width guides 63 of roll stand 61 to the proper width for the strip being processed. After the strip passes rolls 59 and 60 it opens switch 65 in wire 148 and switch 66 in wire 110. When switch 65 opens motor 50 stops and valve 49a exhausts cylinder 49, permitting spring 66 to raise arm 53 and roll 55.

Movement of plate 43 is limited in both directions by an arm 151 which is arrested by frame 25 and plate 64. As the coil 11 continues to grow smaller the feeler arm of switch 46 becomes more and more horizontal until it closes switch 46 in wire 121 of the reversing circuit of motor 33. The unreeling of coil 11 continues until the end of the strip is drawn from arbors 29 and face plates 40. This releases face plates 40 and arm 36 of switch 37, closing contacts 37a and opening contacts 37b, 37c, 37d and 37e. This closes the reversing circuit of motor 24 which lowers lift table 20 until the arm of switch 38 is depressed, opening contacts 38b. The opening of contacts 37e prevents premature action of solenoid valve 41a.

As the end of the strip passes over and releases the depressed arm of switch 48 the arm rises, opening contacts 48a and closing contacts 48b, 48c, 48d, and 48e. Contacts 48c complete the reversing circuit of motor 33 which separates trunnions 68 until stopped by the opening of contacts 129a and 129b of switch 129. As the end of the strip passes over switches 65 and 66 the respective contacts of the switches in the drive circuits of motors 24 and 50 and solenoid valve 49a are closed.

40 The closing of switch 66 completes the drive circuit of motor 24 and the cycle of operation is repeated with a new coil 11.

The selsyn pairs 26, 27 and 62a, 63a may be replaced by a mechanical equivalent where space and construction permit. Fig. 3 shows one such arrangement replacing selsyns 26, 27. Arm 28 is provided with a rack portion 152 which meshes with a pinion 153. A vertical rack area 154 is fastened to switch 32 and meshes with a wide pinion 155 meshed with pinion 153. As arm 28 moves to the left arm 154 and switch 32 are raised an equal amount. Locking solenoid 115 and delay condenser 116 operate the same as before. A linkage arrangement could replace selsyn pair 62a, 63a.

Fig. 4 shows another form of strip starter which may be made as fully automatic as that just described, but lends itself as readily to operator control. A coil 11 having an end 12 and channel 13 is raised into position by lift 200 and pushed onto rolls 201 which are geared to revolve together. Frame 25 has an extension 202 which carries a slide 203 on which is mounted a double acting cylinder 204 with one end of piston rod 205 fastened to member 206 on extension 202. Slide 203 has a cylindrical guide member 207 at one end thereof with flanged ends 208 having end portions 209 extending beyond member 207. Ribs 210 lend support and rigidity to the structure.

Double acting cylinder 204 has two solenoid operated valves 211 and 212 connected to control switches 213 and 214 on operator's control panel 215 by suitable wiring 216.

75 A slide 43 having a tapered nose 44 and side

guide flangings 47 is slidably mounted on plate 64 and is movable to and from coil 11 under the action of cylinder 41 and compression spring 218 which is between a wall of frame 25 and member 219 which is attached to slide 63 and acted on by the piston rod of cylinder 41. Cylinder 41 is operated by a solenoid valve 220 connected by wires 221 to switch 222 on panel 215. Valve 220 is self bleeding on release as are valves 211 and 212.

Curved guide plate 223 is pivoted at 224 on frame 25 and has curved depending flange portions 225 which fit just outside flanged end portions 209 of member 207. Curved plate 223 is long enough to overlap cylindrical member 207 and stops at offset 226 to allow room for strip depressing roller 227. Plate 223 has a continuation 228 which rests on the upper edges of guide 47 when plate 223 is in active position. Plate continuation 228 mounts a housing 229 carrying a cylinder 230 for actuating depressing roller 227. Spring return cylinder 230 has a solenoid valve 231 connected by wires 232 to panel switch 233.

Curved plate 223 is pivoted about 224 by spring return cylinder 234 having a solenoid valve 235 connected to switch 236 by wires 237. It will be understood that all of the operating cylinders in any of the figures of the drawing may be air, hydraulic or electrical solenoids as a matter of design choice. For example a heavy thrust with long travel requires a heavy expensive solenoid and might better be served by an air, oil or water cylinder. If desired roller 227 may be enlarged to correspond with roller 55 and mated with another roller such as 51 in Fig. 1. A drive can then be provided such as motor 50 and roller 227 could be driven by spur teeth as shown in Fig. 1.

The operation of the device of Fig. 4 is as follows:

A coil 11 with end 12 projecting clockwise is placed on cradle lift 200 and unbanded. Lift 200 is raised by a suitable cylinder controlled by switch 238 on panel 215. When in position relative to drive rolls 201 coil 11 is pushed off onto the rolls by a cylinder controlled by switch 239. Indicia marks on rolls 201 will show proper spotting for a coil of given width.

The operator then uses reversing rheostat controller 240 to control the speed and direction of the motor driving rolls 201. When the coil 11 has sufficient clockwise speed the operator closes switch 222 to actuate cylinder 41 and advance nose 44 against the coil to peel off strip end 12 which slides along between guides 47 of slide 43 and continues along plate 64 to the first roll stand 61. This is the simplest case requiring the least equipment and may be regarded as the basic strip starter.

In general, before using controller 240, the operator will close switch 213 as soon as he has checked the position of coil 11 on rolls 201. This causes cylinder 204 to move cylindrical surface 207 with side flanges 208 and projecting portions 209 close to the coil of largest size to be handled. If desired surface 207 can be advanced until it actually comes into contact with coil 11. The operator then closes switch 236, actuating cylinder 234 and pivoting curved plate 223 about 224 until the plate 223 rests on the outside end edge of cylindrical surface 207 or extension 228 rests on the upper edges of guides 47, or both.

Rheostat controller 240 and switch 222 are then operated as just described. If for any reason strip edge 12 is not peeled off cleanly and slips by a cobble is prevented by curved guide 45. Con-

troller 240 can now be reversed to bring edge 12 above nose 44 or to iron out any buckle in it. On the other hand the strip may be continued in clockwise rotation, which is usual with the heavy gauges. While surface 207 may be spiral it is preferred that it not depart very much from the cylindrical as it functions with surface 223 to prevent looping of the strip at the instant end 12 strikes nose 44. If the strip bows up excessively on slide 43 switch 233 is closed and roller 227 presses down and "breaks its back." Where a drive motor is employed roller 227 and a companion may be used to feed the strip to the first roll stand as previously described.

One advantage of the structure of Fig. 4 is that the operator has complete control at all times and may acquire considerable skill in operating drive rolls 201 and nose 44, particularly in the light gauges of strip. This same skill may be utilized in the construction of Fig. 1 in which the manual controls may be employed to arrest the movement of the nose 44 short of actual contact with a coil 11 and thereby assure against any possible scratches on the strip surface. However, for most applications the nose 44 will not scratch if properly finished. In the heavy gauges the problem is largely the application of sufficient force to pry end 12 loose by nose 44. For example the rolls 201 may rotate coil 11 several times to build up momentum before nose 44 is advanced to peel off end 12. With lighter gauges the end 12 may give under impact and partially unreel or it may fold and jam under or above nose 44, causing what is called a cobble. It is with these lighter gauges that surfaces 207 and 223 are most useful. The open space at offset 226 permits the insertion of a bar or other tool.

If desired the arrangement in Fig. 4 may be made partially or fully automatic. Again curved surface 207 may be added to Fig. 1 either above or together with the pivoted surface 223. Where this is done switch 37 may be provided with three additional sets of contacts i. e., 37f initially open and connected to replace switch 213 in wires 216, 37g initially closed and replacing switch 214 in wires 217 and 37h initially open and replacing switch 236 in wires 237. Roller 227 could replace roller 55 and solenoid valve 231 connected between wires 146 and 148 in place of valve 49a.

Nose 44 may be interchangeable to suit strip of various gauges. A short stubby nose of some strength functions best with the heavier gauges of strip. As the gauge becomes lighter the nose 44 may be made more knife-like and curved upward to approach tangency with the coil surface. Again nose 44 may be made somewhat massive and curved upward to fit against the coil in a manner suitable for all gauges. A ground edge will give desirable sharpness for the light gauges and the massive base will provide the strength necessary for the heavy gauges of strip. Care should be exercised that a ground edge on nose 44 does not dig into or gouge the strip. It may be well to polish the ground portion to prevent scratches on the strip surface.

While there have been described what are at present considered to be the preferred embodiments of the invention, it will be apparent to those skilled in the art, that various changes and modifications may be made therein without departing from the spirit or scope of the invention.

I claim:

1. In combination in a strip starter for coiled strip, means to support a coil of strip for rotation, strip peeling means comprising a movable

plate having a relatively sharp nose integrally formed therewith and mounted for movement towards a coil in said support means, first drive means to rotate a supported coil, means to move said strip peeling means toward said coil until said nose engages the strip end of said coil, guide means for directing strip to a desired location for processing, and control means adjacent said guide means and responsive to the presence of a peeled strip for causing said strip peeling means to be retracted from said coil.

2. The combination set forth in claim 1, second drive means to act on a peeled strip, said control means being responsive to the peeled strip and causing the deenergization of said first drive means and the energization of said second drive means.

3. The combination set forth in claim 2, said second drive means comprising a movable roll which acts on the upper surface of the peeled strip end.

4. The combination set forth in claim 3, including means responsive to said control means to move said roll toward the peeled strip and exert a force thereon.

5. The combination set forth in claim 4, means to position a coil of strip on said support means in such a manner that the convex side of a peeled strip end is upward.

6. In combination in a strip starter for coiled strip to be processed, means for supporting a coil of strip for rotation about the coil axis, drive means to rotate the coil about said axis, strip peeling means mounted for movement to strip peeling position and having a nose portion for engaging the end of a coiled length of strip and for peeling it away from the body of a coil to be processed, first guide means for receiving the peeled strip end and directing it away from said coil, and second guide means adjacent said coil and below said nose portion to cause the strip end to be forced back toward said coil if not peeled off said coil above said nose portion.

7. In a strip starter for coiled strip in a strip rolling mill, in combination means for supporting a coil of strip for rotation about the coil axis, drive means to rotate the coil, variable speed reversing control means connected to said drive means, means movable in translation and having an end portion for engaging an end of said strip on a coil, first guide means associated with said movable means to direct the strip end away from said coil means to control the translational movement of said movable means, and second guide means adjacent the normal point of contact of said movable means and said coil for redirecting a strip end toward said coil if peeling onto said first guide means is not effected.

8. In a coil strip starter, means for supporting a coil of strip for rotation, first drive means to rotate a supported coil in a desired direction, movable guide means having a peeling nose for engaging a strip end, means to move said guide means and said nose into engaging relation with a strip end, to peel said strip end therefrom, second drive means movably engageable with said strip end, and control means adjacent said guide means and responsive to said strip end for rendering said first drive means inoperative and for rendering said second drive means operative.

9. In combination in a strip starter for coiled strip to be processed, means for supporting a coil of strip for rotation about the coil axis, coil drive means to rotate said coil on said support means, strip peeling means mounted adjacent said sup-

port means, means to move said strip peeling means and said coil relative to each other into strip peeling relation, means to grasp a strip end and pull strip from the coil, and a control means responsive to said strip end to deenergize said coil drive means and said means for relative movement and to energize said means to grasp a strip end when said strip end reaches a predetermined position with respect to said coil.

10. The combination set forth in claim 9, curved guide means for the end of a coil of strip.

11. The combination set forth in claim 10, including further control means for moving said curved guide means toward a coil mounted in said support means.

12. The combination set forth in claim 11, said further control means including means to reverse the direction of rotation of a coil supported for rotation.

13. In a strip starter for coiled strip to be processed, platform means for receiving a coil of strip, first sensing means adjacent said platform means for detecting the presence of a coil on said platform means and for detecting the diameter of said coil, movable supporting means positionally responsive to said sensing means, means moving said coil from said platform means to said supporting means, first drive means for rotating said coil on said supporting means, movable guide means adjacent said supporting means, said guide means having a peeling nose for engaging a strip end, means causing said guide means to move toward and into contact with said rotating coil whereby a strip end of said coil is peeled onto said guide means, second drive means adjacent said guide means and selectively engageable with a strip on said guide means, and second sensing means on said guide means responsive to the presence of strip thereon for deenergizing said first drive means and for energizing said second drive means.

14. The system of claim 13 including loading means adjacent said platform means for receiving a plurality of coils to be processed, and means responsive to said first sensing means for releasing individual coils from said loading means to said platform means.

15. The system of claim 13 in which said supporting means and platform means are relatively movable in two dimensions, whereby said supporting means may be adjusted to coils of differing diameters to thereafter grip a coil at its axis of rotation.

16. The system of claim 15 in which said supporting means comprises spaced supporting portions, said means for moving said coil from said platform means to said supporting means comprising lift means coupled to said platform means and positioning a coil on said platform means between said spaced supporting portions.

17. The combination set forth in claim 9, and overriding manual control means connected to supersede said control means responsive to said strip.

18. The combination set forth in claim 17, means to position a coil on said means for supporting a coil comprising a movable table and coil detecting and measuring means controlling in part the movement of said table, said means for supporting comprising relatively movable arbors with respect to which said coil detecting and measuring means controls the movement of said coil positioning means, means to move said arbors with respect to each other and switch means positioned and connected to determine the

movement of arbors so as to support a coil for rotation.

19. In combination in a strip starter for coiled strip, means to support a coil of strip for rotation in strip peeling position, strip peeling means comprising a movable member having a strip engaging nose portion on a part thereof extending toward a coil of strip positioned to be peeled, said peeling means being mounted for movement to and from coil position on said support means, drive means for said means to support for rotation a supported coil, means to move said member and said strip engaging nose portion into strip peeling engagement with a coil in position to be stripped, guide means for directing peeled strip to a desired location for processing, first control means for said drive means, second control means for said means to move said movable member and nose portion and overriding manual control means connected to supersede said first and second control means.

20. The combination set forth in claim 19, said first and second control means comprising switches actuated by said strip.

21. The combination set forth in claim 20, coiled strip supply means comprising means to support a plurality of coils of strip ready for peeling, movable stop means for said coils constructed to control their sequential advance, coil positioning means, means constructed to determine the presence of a coil on said positioning means, said coil positioning means constructed to position coils sequentially on said means to support a coil for rotation.

22. The combination set forth in claim 21, said means to determine the presence of a coil comprising feeler arm means constructed to measure the effective radius of a coil of strip on said positioning means and being also constructed to control the movement of said positioning means with respect to said means to support a coil for rotation so as to position a coil to be peeled accurately with respect to said means to support.

23. The combination set forth in claim 19, said first and second control means comprising switches actuated by said strip, strip gripping means constructed to receive a peeled end of strip, to exert an unwinding force thereon and to direct the strip end to a point of further processing.

24. The combination set forth in claim 23, said strip gripping means comprising relatively movable spaced rollers arranged to receive a strip end therebetween, drive means for at least one of said rollers controlled by said strip.

25. The combination set forth in claim 24, said gripping rollers being mounted on and carried by the movable member of said peeling means, one of said rollers being bodily movable toward the other of said rollers in response to the presence of strip therebetween.

26. The combination set forth in claim 19, a pivoted strip guide member mounted adjacent said strip peeling means and constructed to cover a portion of a coil in position to be peeled and the said nose portion and means to pivot said pivoted guide member into guiding position.

27. The combination set forth in claim 26, secondary guide means located below said nose portion and adjacent said coil and curved to move a strip end not engaged by said nose portion toward the body of a coil being peeled.

28. The combination set forth in claim 27, additional guide means movably mounted to cooperate with said pivoted guide member to surround and enclose the upper side of a coil being peeled and to aid in guiding strip being peeled to a point of subsequent handling.

29. The combination set forth in claim 19, said overriding manual control means being connected to supersede selectively said first and second control means, and strip gripping means carried by said movable member constructed to aid in the peeling of strip from a coil.

30. In combination in a strip starter for coiled strip, means to support a coil of strip for rotation in strip peeling position, strip peeling means comprising a member having a strip engaging nose portion on a part thereof extending toward a coil of strip positioned to be peeled, said peeling means and said means to support a coil in strip peeling position being relatively movable into and out of strip peeling relation, drive means for said means to support a supported coil for rotation, means to cause said relative movement into strip peeling engagement position, guide means for directing peeled strip to a desired location, a first control means for said drive means, a second control means for said means to cause said relative movement into and out of strip peeling relation and overriding manual control means connected to supersede at least one of said control means.

31. The combination set forth in claim 30, said overriding manual control being connected to supersede selectively said first and second control means.

32. The combination set forth in claim 31, said means to support a coil of strip for rotation comprising a pair of arbors mounted for movement along the longitudinal axis of a coil mounted to be peeled, said member having a strip engaging nose portion having strip gripping roller means mounted thereon constructed to pull strip from a coil.

33. The combination set forth in claim 32, coil positioning means arranged to position a coil on said means to support a coil for rotation, means to move said coil positioning means from coil receiving position to coil positioning position and back to coil receiving position comprising drive means, means to measure coil diameter, stop means controlled by said diameter measuring means and return means controlled by the movement of said arbors.
